184,822

COMBINED ASH TRAY, CAN AND BOTTLE OPENER, AND FISH SCALER

Johnny Mann, Wabash, Ind.

Application May 9, 1958, Serial No. 50,823

Term of patent 14 years

(Cl. D85—2)

Figure 1 is a plan view of the combined ash tray, can and bottle opener, and fish scaler showing my new design;

I claim:

The ornamental design for a combined ash tray, can and bottle opener, and fish scaler, substantially as shown.
